By Attorney *E. A. Kelly*

UNITED STATES PATENT OFFICE.

FRANK L. DAVIS, OF READING, PENNSYLVANIA.

DESIGN FOR A WAGON-BODY.

SPECIFICATION forming part of Design No. 34,694, dated June 25, 1901.

Application filed May 23, 1901. Serial No. 61,630. Term of patent 3½ years.

To all whom it may concern:

Be it known that I, FRANK L. DAVIS, a citizen of the United States, residing at Reading, in the county of Berks and State of Pennsylvania, have invented and produced a new and original Design for a Wagon-Body; and I do hereby declare the following to be a full, clear, and exact description of the same, reference being had to the accompanying drawings, forming a part thereof.

This invention relates to a new and original design for a wagon-body.

The invention is fully described in the following specification and illustrated in the accompanying drawings, in which—

Figure 1 is a side view, and Fig. 2 a front end view, of my design.

The top portion *a* is rounded crosswise and has an extension *b* at its forward end, which extension is curved and reaches nearly to the front of the body portion.

The body portion *c* is rectangular and has a rectangular portion *d* depending therefrom, which portion is slightly narrower and shorter than the portion *c*. The top portion *a* is joined to the body portion *c* by four uprights *e*, one near each corner, and a ledge or shelf *g* extends the full length of the body portion at either side.

What I claim, and desire to secure by Letters Patent, is—

The design for a wagon-body substantially as shown and described.

In testimony whereof I affix my signature in presence of two witnesses.

FRANK L. DAVIS.
